UNITED STATES PATENT OFFICE

166,478

COMBINED RECEPTACLE AND CLOSURE
MEMBER THEREFOR

Harry A. Mart, Chicago, Ill.

Application October 12, 1951, Serial No. 16,925

Term of patent 14 years

(Cl. D58—26)

To all whom it may concern:

Be it known that I, Harry A. Mart, a citizen of the United States, residing at Chicago, in the county of Cook and State of Illinois, have invented a new, original and ornamental Design for a Combined Receptacle and Closure Member Therefor, of which the following is a specification, reference being had to the accompanying drawing, forming a part thereof.

Fig. 1 is a fragmentary front elevational view of a combined receptacle and closure member therefor showing my new design;

Fig. 2 is a right side elevational view thereof, the view from the opposite side being identical; and

Fig. 3 is a top plan view thereof.

The dominant features of my design reside in the portions shown in full lines.

I claim:

The ornamental design for a combined receptacle and closure member therefor, substantially as shown and described.

HARRY A. MART.
